DESIGN FOR A DRAFTING TABLE

Louis La Pidus, Brooklyn, N. Y.

Application January 15, 1946, Serial No. 125,567

Term of patent 14 years

(Cl. D33—14)

To all whom it may concern:

Be it known that I, Louis La Pidus, a citizen of the United States, residing at Brooklyn, in the county of Kings and State of New York, have invented a new, original, and ornamental Design for a Drafting Table, of which the following is a specification, reference being had to the accompanying drawings, forming a part thereof.

Figure 1 is a side elevational view of a drafting table, showing my new design;

Figure 2 is a front elevational view; and

Figure 3 is a perspective view thereof.

I claim:

The ornamental design for a drafting table, as shown.

LOUIS LA PIDUS.
